COMPUTER

James D. Ferguson, United States Navy,
Arlington, Va.

Application May 28, 1945, Serial No. 596,257

1 Claim. (Cl. 235—61.5)

(Granted under the act of March 3, 1883, as
amended April 30, 1928; 370 O. G. 757)

1

This invention relates to computing devices, and particularly to improved means for rapidly determining at frequent intervals, or at any desired time, the value of a continuously changing unknown. An important object of the invention is to provide such a device which derives its solutions from a plurality of known factors, one or more of which known factors may be introduced automatically by the normal operative movements of apparatus to which the computations are related.

The invention finds particular utility in the field of fire control, especially in connection with the operation of antiaircraft guns of larger calibers, where it supplies in a rapid and reliable manner the data required for effective fire by the so-called "line of sight barrage" method, in which a series of rounds with the same fuze setting is fired as quickly as possible from the gun as the target is tracked, all of the rounds being aimed so that they will burst directly along the line of sight from gun to target.

An important object of the invention is to provide a lead angle computing device of very simple and rugged character, which is adapted to be mounted directly on a gun without requiring connection to any remotely located apparatus and which is accordingly adapted to serve as a standby means of fire control for guns normally controlled by automatic directors.

An object related to that last stated is to provide such an extremely simple lead computing device which is adapted to be installed by securing the same directly to the sight yoke or equivalent part of a gun and which enables accurate local control of the gun, furnishing to the sight setter the data by which he is enabled to deflect the line of sight, by reference to a dial-like chart in a manner analogous to "follow the pointer" operation, in such wise as constantly to incorporate an effective "lead" or sight angle.

The preferred construction herein disclosed is designed for shipboard use against targets employing horizontal or glide bombing tactics and only when the ship itself is attacked. Under such conditions, since the attacking aircraft is moving substantially in a vertical plane through the gun position, variations in the approach angle express themselves in elevation only. Advantage is taken of this fact to simplify the problem and the mechanism by which it is solved.

An additional object of my invention, therefore, is to provide a computer mechanically responsive to gun movement in a vertical plane, which computer will utilize such gun movement automati-

2

cally to provide fire control data, thereby obviating the necessity of estimation of such data by a member of the gun crew.

For a better understanding of the invention, reference may be had to the following drawings in which

Fig. 1 is a front view of a computer designed for use with a 3"/50 cal. gun and represents the preferred embodiment of the present invention;

Figs. 2, 3 and 4 are back, side elevation and plan views, respectively, of the computer shown in Fig. 1, Fig. 3 being partly in section.

Fig. 5 is a graphical representation of a line of sight barrage attainable by means of this invention;

Fig. 6 depicts the computer of the invention mounted on a 3"/50 caliber gun.

Referring specifically to Fig. 6, the computer, shown generally at 10, is rigidly mounted to sight yoke 11 with the face of the computer in a vertical plane through the bore axis of gun barrel 12 when the latter and pointer's sight 13 are both aimed at a point on the horizon. In repelling an attack by a horizontal or glide-bombing airplane, the pointer, by operating pointer's crank 14, elevates the gun barrel 12 to bring his sight 13 on the target. In so doing, the sight yoke 11 is also rotated in elevation through a vertical plane causing the computer to operate as hereinafter described. The sight-setter takes his elevation values in minutes of arc from the computer and translates them into sight corrections for pointer's sight 13. This is done by the sight-setter's operation of range-setting crank 15 which raises or lowers sight bar 17 through a gear arrangement (not shown); movement of the sight bar causes a raising or lowering of the after end of sight yoke 11 to which it is rigidly fixed, and the sight yoke in turn imparts its angular displacement to the pointer's sight 13.

Referring now to Figs. 1, 2, 3 and 4 for a detailed description of the invention, the computer assembly essentially comprises a quadrant-shaped data plate 19 and a pendulum 20, the latter being on a pivot assembly 22 carried by support plate 21. The data plate 19 is also mounted on and swingable about the pivot 22 but normally held against such movement and additionally secured by the thumb nut 34 and bolt 33. Mounting bracket 23 is permanently but pivotally fixed at one end to support plate 21 by rivet 25; relative movement between mounting bracket 23 and support plate 21, for adjustment purposes, is afforded by slot 26 through which protrudes bolt 27 which is fixed to support plate 21. Wing nut,

28 secures the support plate in the desired position relative to the mounting bracket.

Data plate 19 contains a number of values of sight angle in minutes of arc arranged in concentric arcs as shown. These values are calculated mathematically from the various conditions of target motion influencing speed of elevation of the line of sight. Corresponding with each arc of sight angle values is a number-letter designation on the pendulum 20. These are arranged in a vertical series generally designated 39, and will presently be more fully explained. As the data card 19 rotates in response to gun elevation, it sweeps under pendulum 20. Proper values of sight angle are then read from the data plate 19 through window 29 in the pendulum by the sight-setter, who "cranks" them into pointer's sight 13 as previously described.

The above discussion relates only to attacks by horizontal bombers. When the area surrounding the gun position is under attack by a glide bomber, the data plate 19 is rotated on support plate 21 until the index 30 on the latter is opposite the estimated angle of glide on scale 31 of data plate 19. Bolt 33 and knurled knob 34 secure the data plate 19 and support plate 21 in any desired position within the limits of arcuate slot 35. Guides 36, fixed securely to support plate 21, assure substantial juxtaposition of the latter and data plate 19. Stop pins 41 of data plate 19 prevent pendulum 20 from swinging beyond the functional area of the data plate.

Example.—In Fig. 5, the target 37, shown in three successive positions it occupies during a bombing run, is presumed to be a horizontal bomber attacking the ship 38 mounting gun 12 equipped with the computer of this invention. As target 37 approaches, the gun captain calls out the proper number-letter designation to be used by the sight-setter in establishing and maintaining a line of sight barrage 40. The number-letter designation is selected from the series 39 carried by the pendulum 20. The number forming the first part of this designation refers to fuze setting in seconds; the letter, to the angular speed of elevation of the pointer's sight to keep on the target. If the number-letter designation was correctly estimated by the gun captain, the sight angles on the computer appearing under the window of the pendulum opposite this designation will furnish the sight-setter with proper sight angles to maintain a line of sight barrage. If, however, a burst appears behind the target, the

next lower fuze setting should be used and the number-letter designation changed accordingly. For instance, if the target penetrates an "8H" barrage, the proper procedure is to shift to a "6H" barrage. Also, if the bursts do not lie in the line of sight, the original letter of the number-designation was wrong and the gun captain should order a new letter. If the burst was low, a new letter earlier in the alphabet should be ordered; if the burst was high, a new letter later in the alphabet should be used in the number-letter designation.

While I have described only one embodiment of my invention, namely, a computer designed for use with a specific gun, 3"/50 caliber, having a muzzle velocity of 2700 F. P. S., it will be obvious to those skilled in the art that various changes and modifications may be made therein without departing from the invention, and the appended claim is intended to cover such changes and modifications as fall within the true spirit of the invention.

The invention herein described may be manufactured and used by or for the Government of the United States of America for governmental purposes without the payment of any royalties thereon or therefor.

I claim:

A sight angle computer adapted to be attached to the sight yoke of an elevational gun including a supporting plate adapted to be secured to and be movable with said yoke, a data scale member pivotally carried by and independently adjustable with respect to the plate, means for securing the plate and member together in adjusted position, and an indicia carrying pendulous arm pivoted at the pivot of said scale member and depending vertically over and sweeping said member, its indicia co-operating with the swept data scale to determine a desired sight angle.

JAMES D. FERGUSON.
